UNITED STATES PATENT OFFICE.

RALPH A. WALDMAN, OF SAN FRANCISCO, CALIFORNIA.

MILK-BOTTLE CASE.

1,125,781.

Specification of Letters Patent. Patented Jan. 19, 1915.

Application filed July 24, 1912. Serial No. 711,336.

To all whom it may concern:

Be it known that I, RALPH A. WALDMAN, a citizen of the United States, residing in the city and county of San Francisco, State 5 of California, have invented a new and useful Improvement in Milk-Bottle Cases, of which the following is a specification.

My invention relates to cases for milk bottles, wherein empty milk bottles are 10 placed, as they are received from the consumer, and remain while they are being washed, filled, capped and during transportation back to the consumer.

The objects of my invention are, first, 15 sanitation, second, cheapness and simplicity of construction, third, durability, fourth, to provide means for retaining the bottles in the case while the same is inverted when passing through the washing machine, and 20 to prevent the bottles from being jarred and jolted during transportation, and thus eliminate the noise consequent upon such jarring, and fifth, to provide means for preserving the alinement of the cases when the 25 same are stacked in the refrigerator or during transportation, and sixth, to provide a case which will allow free circulation of cold air around the bottles during the process of refrigeration.

30 For a clear comprehension of my invention reference should be had to the accompanying drawings forming part of this specification, in which—

Figure 1 is a broken plan view of my milk 35 bottle case, disclosing the construction thereof. Fig. 2 is a broken side elevation, disclosing more fully the retaining springs integral with the corrugated partitions. Fig. 3 is an enlarged detail view of one 40 corner of two stacked cases disclosing the method of preserving the alinement.

I am aware that heretofore milk-bottle cases have been invented and are in use for 45 transporting milk-bottles through washing machines and back to the consumer. Some cases are constructed of wood having partitions and bottoms of longitudinally and transversely disposed rods, also inserted or attached devices at each of the four upper 50 corners for preserving the alinement of the cases when stacked. Other cases have been constructed of metal sides and ends, with partitions and bottoms similar to those in the wooden cases. Both cases have proven 55 unsatisfactory for the following reasons.

The wooden cases necessitate the applica-

tion of a metal re-inforcing strip around each end and metal shoes attached to each of the four lower corners to lessen the wear caused by friction while the case is being 60 pushed through the washing machine.

The strong detergent that is used to cleanse the bottles causes rapid disintegration of the wooden portion of the cases, and consequently the cases wear out in a very 65 short length of time. Also, the disintegration of the wooden portion of the cases produces a moist pulp which is sometimes transferred to the bottles after the same have left the washing machine, necessitating the re-washing of the bottles in another case. To 70 obviate this condition other boxes are made with metal sides and ends.

Both metal and wooden boxes with closed 75 sides do not fully expose the filled bottles to the cold air currents in the refrigerator when the cases are stacked. Also the style of case now in use have no means for retaining the bottles within the cases when the 80 said cases are inverted while going through the washing machine. To retain the bottles within the cases during the operation a retaining frame is placed over the cases before they are inverted and must be removed 85 when the cases have passed through the washing machine.

A further disadvantage of the metal cases 90 is that they create considerable noise when the action of the vehicle in which they are being transported to the consumer, jars the bottles and causes them to come into contact with the sides of the said metal case.

My invention is designed to overcome these several disadvantages as well as to provide a case that is light, simple and of 95 open construction, durable and sanitary, also to provide a case where no separate retaining frame is required to retain the bottles when the same is inverted in the washing machine and has no separate means for 100 alinement.

The numeral 1 is used to designate an upper rectangular frame, preferably of angle iron, to which a similar lower frame 2 is secured by means of corner angles 3. The 105 upper ends 3' of the corner angles 3 extend above the upper surface of the upper rectangular frame 1, while the lower ends of the said angles are recessed as at 3". The angles 3 are secured in this manner so that 110 when the cases are stacked one on the other the upper ends 3' of the lower case will en-

gage the inner surface of the lower rectangular frame 2 and preserve the alinement of the cases so stacked, (Fig. 3). A further object of this arrangement is that the weight of the upper cases will be borne partly by the corner angles 3, and thus relieve the shear on the rivets uniting the vertical and horizontal angles, the angles 3 being capable of sustaining a greater weight by reason of their perpendicular position than the horizontal angles comprising the horizontal frames 1 and 2.

An intermediate frame 4, having a longitudinal member 4', is secured to the corner angles 3. Riveted to the frame 4 and the member 4' are corrugated strips 5 having springs 5' integral therewith and adapted to engage and retain the bottles B in pockets formed by the corrugations of the strips 5, when the case is inverted.

Supporting strips 6, reinforced by the lateral members 6', are secured to the lower frame 2 for the support of the bottles in the case.

The bottles B when received from the consumer, are placed in the pockets formed by the corrugated strips 5 and retained therein by means of the springs 5'. The tension of these springs 5' is sufficient to retain the bottles B within the case when the same is inverted while going through the washing machine. This holds the bottles in such a position that the streams of water are free to enter the bottles and also to allow the same to drain thoroughly before they are again turned upright.

In the cases at present in use, the retaining frames are removed as soon as the cases are removed from the washing machines necessitating the reversing of the case so that the bottles will remain therein. Any water that is left adhering to the insides of the bottles must necessarily drain into the bottles. Should the cases containing the bottles be left in an inverted position for the purpose of draining, a greater number of retaining frames would be required in order to accommodate the draining cases as well as the cases passing through the washing machine.

It is evident from the foregoing that I have provided a case that is simple of construction and consequently can be produced cheaply.

The lack of large surfaces and wooden corners, produces a sanitary case, inasmuch as it can easily be cleaned or sterilized without causing disintegration. The open nature of its construction is adapted to freely admit the cooling air currents of the refrigerator and at the same time, materially lessen the weight of the case.

The integral means for retaining the alinement of the cases when stacked, is an advantage, inasmuch as they are produced

without additional cost and, being integral with the frame, possess greater stability than any attached device.

The details of construction are so susceptible to change that I do not wish to confine myself to the precise construction shown herein, but rather to avail myself of any modification that may fall properly within the scope of my invention as, for instance, the pockets may be formed of a series of 75 rings riveted together.

Having thus described my invention what I claim as new and desire to secure by Letters Patent is:

1. A milk bottle case comprising upper 80 and lower rectangular frames; corner angles uniting the said upper and lower rectangular frames; an intermediate frame secured to the corner angles; a centrally disposed longitudinal bar secured to the intermediate 85 frame; corrugated strips secured to the intermediate frame and centrally disposed longitudinal bar; and longitudinal supports secured to the lower rectangular frame and lying below and between the corrugated 90 strips.

2. A milk bottle case comprising upper and lower rectangular frames; corner angle iron secured to the upper and lower frames and having the upper ends extending above 95 the upper frame and the lower ends thereof receded within the lower edge of the lower frame; an intermediate frame secured to the corner angle irons between the upper and lower frames; corrugated strips secured to 100 the intermediate frames and adapted to form pockets for the reception of milk bottles; means integral with the corrugated strips and adapted to retain bottles within the pockets when the case is inverted; and 105 means secured to the lower frame and adapted to support bottles within the pockets when the case is upright.

3. A milk bottle case comprising upper and lower rectangular frames; corner angle 110 irons secured to the upper and lower frames and having the upper ends extending above the upper frame and the lower ends thereof receded within the lower edge of the lower frame; an intermediate frame secured to the corner angle irons between the upper and lower frames; a centrally disposed longitudinal bar secured to the intermediate frame; corrugated strips secured to the intermediate 115 frame and centrally disposed bar and 120 adapted to form pockets for the reception of milk bottles; spring fingers integral with the corrugated strips and adapted to retain milk bottles within the pockets when the case is inverted; and means secured to the lower frame and adapted to support the bottles within the pockets when the case is upright.

4. A milk bottle case comprising upper 125 and lower rectangular frames; corner angle 130

5   irons secured to the upper and lower frames and having the upper ends extending above the upper frame and the lower ends thereof receded within the lower edge of the lower frame; an intermediate frame secured to the corner angle irons between the upper and lower frames; a centrally disposed longitudinal bar secured to the intermediate frame; corrugated strips secured to the 10 intermediate frame and centrally disposed bar and adapted to form pockets for the reception of milk bottles; spring fingers integral with the corrugated strips and adapted to retain milk bottles within 15 the pockets when the case is inverted;

and longitudinal straps secured to the lower rectangular frame and directly under the pockets formed by the corrugated strips and adapted to support bottles within the pockets when the case is upright; and lateral 20 straps secured to the longitudinal straps and to the lower rectangular frame.

In testimony whereof I have hereunto set my signature in the presence of two subscribing witnesses.

RALPH A. WALDMAN.
